UNITED STATES PATENT OFFICE.

JOSEPH T. BRENEMAN, OF EL CERRITO, CALIFORNIA.

SPECULUM AND DILATOR.

Application filed November 9, 1922. Serial No. 599,867.

To all whom it may concern:

Be it known that I, JOSEPH T. BRENEMAN, a citizen of the United States, residing at El Cerrito, in the county of Contra Costa 5 and State of California, have invented certain new and useful Improvements in Specula and Dilators; and I do declare the following to be a full, clear, and exact description of the invention, such as will enable 10 others skilled in the art to which it appertains to make and use the same.

My invention relates to improvements in specula and dilators and has for its object to improve upon the construction shown by my 15 U. S. Patent No. 1,018,868, of February 27, 1912. In the patented device, a main pair of levers are fulcrumed to each other between their ends and carry laterally extending dilator fingers at their front ends, while 20 the rear ends of said levers constitute the handles for the instrument. A pair of supplemental levers are connected for both sliding and pivotal movement to the main levers, the front ends of said supplemental levers 25 being provided with additional dilating fingers, while their rear ends are slidably connected with the handle-forming ends of said main levers. Means are provided to cause opening and closing of the main levers to 30 slide the supplemental levers longitudinally while swinging them around their pivots, but the object of the present invention is to improve upon this sliding means for the supplemental levers, whereby to provide an 35 instrument which may be more smoothly and easily operated, and which will present other advantages.

The means above referred to for imparting longitudinal sliding movement to the 40 supplemental levers is disposed in advance of the pivotal connection between the main and supplemental levers and actual use of the instrument has disclosed that this is not the most advantageous point for disposition 45 of the means under consideration. With the patented construction, in order to obtain free movement, it was found necessary to employ a lubricant which was difficult to keep sterile and thorough asepsis was impossible. As 50 this lubricated surface was very close to the operative area, there was great danger of infection from this source. Hence, it was found advisable and practical to dispose the means under consideration at a point inward 55 of the main pivot for the levers so as to provide a more practical construction and

to dispose the same at a point remote from the operative area.

With the foregoing in view, the invention resides in the novel subject matter hereinafter 60 described and claimed, the description being supplemented by the accompanying drawings.

Fig. 1 is an edge elevation of a dilator constructed according to my invention. 65

Fig. 2 is a side elevation with the dilating fingers in section, the instrument being shown in closed position.

Fig. 3 is substantially a duplicate of Fig. 2 with the exception that it illustrates the 70 dilating fingers in an expanded position.

Figs. 4, 5, 6 and 7 are detail sectional views as indicated by lines 4—4, 5—5, 6—6 and 7—7 of Fig. 2.

In the drawings above briefly described 75 the numeral 1 designates a pair of suitably shaped levers which are fulcrumed to each other near their front ends, as shown at 2. The front ends of these levers are curved or bowed away from each other and are provided with laterally extending dilating fingers 3^a, while the rear ends 4 of said levers 80 constitute a pair of handles for operating the instrument, the construction being such that when these handles are forced toward 85 each other, the dilating fingers 3^a are moved away from each other.

The numeral 5 designates a pair of supplemental levers which contact with the outer sides of the levers 1 and are connect- 90 ed with said levers 1 by suitable headed fulcrum screws or the like 6 which pass through slots 7 in the levers 5. By any suitable means 8, the rear ends of the sup- 95

plemental levers 5 are slidably and pivot- 100 ally connected with the rear portions of the levers 1, so that when the dilating fingers 3^a on the front ends of the levers 1 move away from each other, the additional dilat- 105 ing fingers 3 on the front ends of the levers 5 will also recede from each other. Novel means are provided also, for the purpose of sliding the supplemental levers rearwardly to move the fingers 3 away from the fingers 3^a, simultaneously with movement of all of 110 said fingers away from each other. In the present showing, each of the levers 1 is widened behind its fulcrum and the widened portions are provided with oblique cam slots 9 which are preferably longitudinally curved, said slots receiving projecting studs 10 on the levers 5.

By the construction shown, when the handles 4 are moved towards each other to spread the dilating fingers 3^a, the supplemental levers 5 are moved in the same manner, with the exception that they are slid rearwardly by the studs 10 and slots 9. Similarly, when the handles 4 are forced away from each other to contract the dilator, the studs 10 and slots 9 force the levers 5 again forwardly.

The improved construction is greatly advantageous over that shown in the patent above referred to, and an instrument is provided which will operate more smoothly. It will also be observed that the new form of device gives a wider field for observation and operation, insures greater ease and certainty of operation, and removes the danger point of infection farther from the operative wound, and the construction is comparatively more simple than the original device. Hence, even though the change in construction appears to be small, it has converted what has heretofore been a more or less impractical device into one which is highly practical and safe to use.

As excellent results have been obtained:

from the details disclosed, they are preferably followed, but within the scope of the invention as claimed, numerous minor changes may be made.

I claim:

In combination, a pair of levers pivoted together between their ends and having dilating fingers at their front ends, a second pair of levers at the outer sides of said first named levers and connected slidably and pivotally between their ends to said first named levers, the front ends of said second pair of levers having dilating fingers while the rear ends thereof are slidably connected with the handle-forming rear ends of said first named levers, and means for effecting longitudinal movement of said second pair of levers when swung on their pivots, by the other levers, said means being disposed at a point spaced rearwardly from the aforesaid pivot and comprising studs on one pair of levers and oblique cam slots in the other pair of levers receiving said studs.

In testimony whereof I have hereunto affixed my signature:

JOSEPH T. BRENEMAN.
